UNITED STATES PATENT OFFICE.

THEODORE L. HELSABECK, OF BRANDFORD, FLORIDA.

PROPELLER.

1,375,907.

Specification of Letters Patent. Patented Apr. 26, 1921.

Application filed January 28, 1921. Serial No. 440,704.

To all whom it may concern:

Be it known that I, THEODORE L. HELSABECK, a citizen of the United States, residing at Brandford, in the county of Suwanee 5 and State of Florida, have invented a new and useful Propeller, of which the following is a specification.

This invention relates to propellers for boats of different types, one of its objects 10 being to provide a propeller formed of a desired number of units mounted for rotation about an axis extending transversely of the path of movement of the boat and each unit including a series of paddles mounted 15 for rotation about individual axes extending radially from the axis of rotation of the units.

A further object is to provide paddles of 20 novel construction adapted, during the rotation of the units, to successively move to feathering and active or propelling positions, means being employed for automatically holding the paddles while in active positions and for automatically uncoupling 25 the paddles so as to permit them to swing out of active and into feathering positions as they pass upwardly and forwardly from the water prior to being directed back into the water at the beginning of the next propelling stroke.

Another object is to provide a propeller which can be readily installed in lieu of 30 propellers of the usual types and which is not only simple and durable in construction but is also of high efficiency.

With the foregoing and other objects in view which will appear as the description proceeds, the invention resides in the combination and arrangement of parts and in 40 the details of construction hereinafter described and claimed, it being understood that within the scope of what is claimed, changes in the precise embodiment of the invention shown can be made without departing from the spirit of the invention.

In the accompanying drawings the preferred form of the invention has been shown.

In said drawings—

Figure 1 is a plan view of the stern portion of a boat and showing a propeller connected thereto and formed of two units such as constitute the present invention.

Fig. 2 is a side elevation of one of the units, a portion of the hub being shown 55 broken away.

Fig. 3 is a bottom plan view of the unit.

Fig. 4 is a central transverse section through one of the units.

Fig. 5 is a detail view of one of the latches of the unit.

Fig. 6 is a detail view of the other latch thereof.

Fig. 7 is a transverse section through a portion of the supporting beam of the propeller and showing the coöperating portions 65 of the beam and paddle for holding the paddle in feathering position.

Fig. 8 is a face view of one of the latch carrying disks.

Fig. 9 is a view showing in diagram the 70 movement of a paddle from feathering to propelling position.

Fig. 10 is a view similar to Fig. 9 and showing the relative positions of the parts during the movement of the paddle from 75 active to feathering position.

Fig. 11 is a view similar to Fig. 9 and showing the paddle in transverse section to indicate the positions of the doors or blades of the paddle.

Fig. 12 is a view similar to Fig. 10, showing the paddle in transverse section to illustrate the positions of the doors or blades.

Fig. 13 is a view partly in side elevation and partly in section showing a modified 85 arrangement of the paddle units.

Referring to the figures by characters of reference A designates the stern portion of a boat from which extend parallel rearwardly projecting beams 2 the lower faces 90 or edges of which are cut away to provide angular recesses 3. The rear ends of the beams are rounded as at 4 so as to be concentric with a transverse shaft 5 journaled in bearings 6 at the inner or upper ends of 95 the recesses 3. This shaft 5 is provided with a gear 7 meshing with a gear 8 on a shaft 9 extending from the hull of the boat so that when the engine on the boat is operated motion will be transmitted to the transverse 100 shaft 5.

Secured to the shaft 5 are spaced propelling units each of which coöperate with one of the beams 2. As both units are of the same construction and operate in the same 105 manner it will be necessary to describe only one of them in detail.

The propelling unit includes a hub 10 secured to the end of shaft 5 and bearing laterally against the outer side of the beam 2, 110 and a disk 11 secured to the shaft 5 and bearing snugly against the inner surface of

the beam 2. Extending into the hub 10 at the inner side thereof are recesses 12 the opposed front and back walls of which converge inwardly to enlargements 13 at the inner ends of the recesses. The recesses and their enlargements are closed at their inner sides by a wear plate or disk 14 which is secured to the hub and is interposed between said hub and the beam 2.

10 A bearing 15 is arranged in each of the enlargements 13 and is supported by a laterally extending pivot pin 16 mounted to rotate within a recess 17 extending laterally within the hub. Swiveled within each of 15 the bearings 15 is a stem 18 mounted to rotate and to slide within the adjacent recess 12 and to the outer end of each stem 18 is secured a paddle frame 19 preferably rectangular as shown and provided, at opposite 20 sides of its longitudinal center with openings 20. Extending in opposite directions from each frame 19 at opposite sides of the axis of its stem 18 are arms 21 having laterally extending fingers 22 on which are 25 journaled anti-friction rollers 23.

The frames 19 have their inner ends spaced from the shaft 5 a distance slightly greater than the distance between said shaft and the periphery of the hub 10 so that said 30 frames are thus free to swing across the hub as shown, for example, in Figs. 3 and 4. Formed in the periphery of the hub 10 adjacent each of the frames 19 is a recess 24 and mounted in this recess is a catch in the 35 form of a leaf spring 25 having tapered heads 26 extending outwardly from its ends and which heads provide shoulders 27 at their innermost ends. The spring 25 is secured at its center to the center portion of 40 the recess and yieldingly supports the heads 26 so that they normally project outwardly from the periphery of the hub 10.

45 Recesses 28 are formed in that face of the disk 11 nearest the beam 2, the ends of this recess being deeper than the middle portion thereof. Secured on the middle portion of the bottom of each recess is the central part of a leaf spring 29 from the ends of which extend oppositely disposed heads 30 the inner ends of which provide shoulders 31. These shoulders do not extend throughout 50 the width of the heads but extending from those ends of the heads nearest the center of the disk 11 are inclined webs 32 converging toward each other as shown particularly in Fig. 6. The heads 30 normally project inwardly away from the disk 11 and are adapted, during the rotation of the disk, to travel within an arcuate groove 33 formed 55 in the adjacent side of the beam 2 and along the path of the heads.

60 Another arcuate groove 34 is formed in the beam 2 opposite the groove 33 and extends from one wall to the other of the recess 3. This groove 34 has its innermost

portion widened as indicated at 35 and that end of the groove opening through the front wall of the recess 3 or, in other words, the wall nearest the hull of the boat, is curved laterally away from the hub 10 as shown at 70 36 in Fig. 9. The other end of the groove 34 is preferably enlarged as shown at 37 in Fig. 10, the outer wall of the groove being rounded at this point of enlargement.

75 Mounted on each of the frames 19 are shutters or blades 38 arranged in pairs at opposite sides of the axis of rotation of the stem 18, the shutters of one pair being located at one side of the frame so as to close one set of openings 20 while the shutters of the other pair are located at the other side of the frame to close the other set of openings 20.

80 It is to be understood that the disk 11 and the hub 10 rotate together and that the catches 25 are located directly opposite the catches 29. The shaft 5 rotates in the direction indicated by the arrows in Figs. 1 and 4 and as each paddle frame 19 travels upwardly and forwardly it lies parallel with the adjoining face of the beam 2 and with one of its arms 21 traveling in the arcuate groove 34. As the paddle frame arrives at the front wall of the recess 3 and as shown by diagram in Fig. 9 the roller carrying finger 22 of the arm 21 will move into the laterally curved end 36 of the groove 34 and impart a slight rotation to the frame 19 and its stem 18. This rotation will be enough to shift the paddle frame out of feathering 90 position as it enters the water adjacent the recess 3 and as the arm 21 and finger 22 move out of the groove 34 the resistance offered by the water to the movement of the paddle frame 19 will result in said frame swinging 95 from the position indicated at *a* in Fig. 9 to the position indicated at *b* in said figure. Thus the shutters or blades 38 at the inner 100 side of the frame 19 will swing to closed position as shown in Fig. 11 while the other shutters on the frame will move to open position. The opposed sides of the shutter frame will engage the catches 25 and 29 adjacent thereto, the inner side of the frame 105 swinging into position between the heads 30 from the position indicated at *a* in Fig. 9 to the position indicated at *b* in said figure. Thus the shutters or blades 38 at the inner side of the frame 19 will swing to closed 110 position as shown in Fig. 11 while the other shutters on the frame will move to open position. The opposed sides of the shutter frame will engage the catches 25 and 29 adjacent thereto, the inner side of the frame 115 swinging into position between the heads 30 so as to engage one of the shoulders 31 while the other side of the frame 19 swings over and depresses one of the heads 26 so as to allow the frame to assume a position between said heads 26. Thus as the frame 19 120 moves rearwardly in the body of water the boat will be propelled forwardly and as the frame 19 reaches the back wall of the recess 3 the inclined web 32 of the head 30 engaging the frame 19 will come against a deflecting tongue 39 extending from the beam 2 and into the recess 3 close to the inner side 125 of the disk 11. Thus the head 30 engaging the frame 19 will be pushed laterally away from said paddle frame and at the same 130

time the finger 22 on one side of the frame 19 will be moved into the enlarged end 37 of the groove 34 by the contact of the frame 19 with the rounded wall of the recess 3, as 5 shown by dotted lines in Fig. 10, this initial position of the paddle frame being designated at *c*. As the arm 21 and its finger 22 continue to travel into the groove 34 the frame 19 will be swung completely around 10 to feathering position as indicated at *d* in Fig. 10, this position continuing as the frame moves back around the shaft 5 to the position *d* indicated in Fig. 9. Thus it will be seen that during the rotation of the shaft 15 5 each of the paddle frames will be maintained in feathering position as it passes in one direction and will be brought to transverse or propelling position as it crosses the recess 3. The opposed faces of each paddle 20 frame are presented successively to active positions so that while one pair of shutters or blades are brought to position to close during the propelling action during one trip across the recess 3, the other set of shutters 25 or blades are closed during the next trip across said recess. In this way wear is evenly distributed upon all of the shutters or blades and instead of being compelled to impart a back and forth rocking movement 30 to the paddle as has heretofore been the practice, each paddle is given an intermittent rotation in one direction, thus insuring accuracy of operation and materially reducing wear upon the parts. 35 When it is desired to reverse the motion of the boat it is merely necessary to reverse the rotation of the shaft 5 whereupon the parts will operate as hereinbefore described but in the reverse manner. 40 Obviously instead of arranging the shaft 5 horizontally as heretofore described the structure can be arranged as shown in Fig. 13. In this figure there are illustrated vertically aligned shafts 40 and 41 journaled at 45 their adjacent ends in a bearing 42 carried by a frame 43. The upper shaft 40 has a gear 44 and the lower shaft 41 has a gear 45. The two gears are driven in opposite directions respectively by a gear 46 secured to the 50 engine shaft 47. Each of the shafts 40 and 41 is journaled within a rearwardly extending beam 48, these beams being superposed and being similar to the beams 2 although arranged with their faces horizontal and 55 with their recesses in opposite sides respectively. The various other parts of the propeller units are the same as have heretofore been described, it being understood that the shafts 40 and 41 correspond with the shaft 5. 60 Whereas in the preferred form of the device the propelling units all rotate in the same direction, in this modified form the units rotate in opposite directions.

What is claimed is:—

65 1. A propeller including spaced revoluble

members, a series of paddles carried by one of the members and mounted for rotation about radial axes, means upon the members for engagement with the paddles to hold them in propelling positions, and means for successively releasing the paddles, shifting them to feathering positions, and maintaining them in feathering positions during part of the rotation of the propeller. 70

2. A propelling unit for boats, including 75 a stationary member having a recess extending thereinto, members at opposite sides of the stationary member and mounted to rotate in unison, paddles carried by one of the members and mounted for rotation about 80 radial axes, said stationary member constituting means for holding the paddles in feathering positions while traveling away from the recess, coöoperating means upon the stationary member and the paddles for successively shifting said paddles about their radial axes to propelling positions while crossing the recess and for returning the paddles to feathering positions after passing the recess, and means for automatically 85 engaging the paddles to hold them in propelling positions while passing the recess. 90

3. A propelling unit for boats including a stationary member having a recess, connected rotatable members at opposite sides of 95 the stationary member and extending across the recess at opposite sides thereof, paddle frames carried by one of the members and mounted for rotation about radial axes, shutters connected to opposite sides respectively of each frame, oppositely extending arms upon each paddle frame, there being an arcuate groove within the stationary member for the reception of the arms to hold the paddle frames in feathering positions while moving away from the recess, and means upon the rotatable members for automatically engaging the paddle frames to hold the same in propelling position while moving across the recess. 100 105 110

4. A propelling unit for boats including a stationary member having a recess and an arcuate guide groove, connected members mounted for rotation at opposite sides respectively of the stationary member, paddles carried by one of the rotatable members and rotatable about radial axes, means carried by the paddles for engaging the guide groove to hold the paddles in feathering positions during a portion of the rotation of 120 the members, and for imparting a rotation to the paddles about their radial axes while moving to position adjacent the recess, and means upon the rotatable members for engagement with the paddles as they are 125 moved successively across the recess, to maintain the paddles in propelling positions. 130

5. A propelling unit for boats including a stationary member having an arcuate guide groove and a recess, connected rotatable 130

members at opposite sides of the stationary member and extending across the recess, paddle frames carried by one of the rotatable members and mounted to rotate about 5 radial axes extending through the center thereof, each paddle including shutters connected to opposite sides of the frame at opposite sides of its axis of rotation respectively, means carried by each frame for engagement with the groove in the stationary member to maintain the paddles in feathering positions during a portion of the rotation of the unit, catches mounted on the rotatable members for engagement with the 10 paddle frames to hold them in propelling positions while moving past the recess, and means for automatically unfastening the paddles from the catches and for shifting the paddles to feathering positions upon 15 leaving the recess.

6. A propelling unit for boats including a radial series of paddles mounted for rotation about a common axis and about individual radial axes, and means for intermittently rotating the paddles about their individual axes during their rotation about the common axis to bring them successively to propelling and to feathering positions.

7. A propelling unit for boats including 20 a radial series of paddles mounted for rotation about a common axis and about individual

axes, means for intermittently rotating the paddles about their individual axes during their rotation about the common axis to bring them successively to propelling and to feathering positions, and catches for automatically engaging opposite sides of each paddle to hold the same in propelling position.

8. A propelling unit for boats including a radial series of paddles mounted for rotation about a common axis and about individual axes, means for intermittently rotating the paddles about their individual axes during their rotation about the common axis 45 to bring them successively to propelling and to feathering positions, catches for automatically engaging opposite sides of each paddle to hold the same in propelling position, means for automatically unfastening 50 the paddles successively from the catches, and means for holding the paddles in feathering positions while released from the catches.

In testimony that I claim the foregoing 55 as my own, I have hereto affixed my signature in the presence of two witnesses.

THEODORE L. HELSABECK.
